UNITED STATES PATENT OFFICE.

CALEB S. GURNEY, OF PORTSMOUTH, NEW HAMPSHIRE.

PNEUMATIC CUSHION FOR VEHICLE-SPRINGS.

No. 838,106.

Specification of Letters Patent.

Patented Dec. 11, 1906.

Application filed December 18, 1905, Serial No. 292,315.

To all whom it may concern:

Be it known that I, CALEB S. GURNEY, a citizen of the United States, residing at Portsmouth, in the county of Rockingham 5 and State of New Hampshire, have invented certain new and useful Improvements in Pneumatic Cushions for Vehicle-Springs; and I do declare the following to be a full, clear, and exact description of the invention, such as will enable others skilled in the art to which it appertains to make and use the same.

My invention relates to improvements in pneumatic cushion devices for the springs of vehicles and the like.

One object of the invention is to provide a simple, durable, inexpensive, and efficient pneumatic cushion of this character which may be readily mounted upon either side of 20 or between the two oppositely-bowed members of a vehicle-spring or in any suitable manner upon springs of any description, so as to ease the violent jolts of a vehicle in passing over uneven ground.

With the above and other objects in view the invention consists of certain novel features of construction, combination, and arrangement of parts, as will be hereinafter more fully described and claimed.

In the accompanying drawings, Figure 1 is a side elevation of a vehicle-spring, my improved pneumatic cushioning device being shown in this instance mounted between the members of the spring. Fig. 2 is a vertical 35 sectional view through the cushioning device removed from the spring, and Figs. 3 and 4 are perspective views of the two telescoping members of the cushion.

Referring to the drawings by characters, 1 40 denotes my improved pneumatic cushion, which may be mounted between the two oppositely-bowed members *s* of a vehicle-spring *S*, or upon either the outer or inner side of said spring, or in any suitable manner upon 45 a spring of any description. The cushioning device comprises two closely-fitting telescoping cylindrical members 2 3. The inner and lower member 3 has a closed bottom and an upper open end 4, adjacent to which may be 50 provided on the exterior of the cylinder an annular band of packing 5 to cause the member 3 to fit more snugly, if necessary, within the member 2. The said member 3 is formed adjacent to its lower end with a longitudinally-extending slot or opening 6, which 55 forms a restricted passage through which air

enters and escapes as the two members of the device are moved toward and from each other. One or more of the slots may be employed, and they may be of any size, according to the size of the cushion and the use to which it is to be put. The outer and upper member 2 has an open lower end 7, into which the open upper end 4 of the member 3 telescopes, and a closed top, which is here 60 shown in the form of a removable screw cap or head 8, but which may be of any other form. Upon the lower end 7 of the member 2 is provided a protecting-hood 9, adapted to surround the lower portion of the member 3 65 and to protect the same from dust and dirt. This hood 9 is in the form of a sleeve of slightly-greater diameter than that of the member 3, so that an annular space 10 is formed between the interior of the hood and 70 the exterior of the lower member 3, as clearly shown in Fig. 2 of the drawings. The hood 9 may be screw-threaded or otherwise rigidly secured upon the lower end of the member 2, or it may be slidably mounted thereon, as 75 shown, or in any other suitable manner. As shown, it is supported thereon by having the inwardly-extending annular flange 11 at its upper end engage a similar outwardly-extending annular flange 12, formed or provided upon the lower end 7 of the member 2. 80

As the member 2 slides over the member 3, the slot or opening 6 will be opened or closed to a greater or less extent, and the passage of air into and out of the cylindrical 85 members will vary to produce an automatic cushioning action. It will be seen that when the two members are forced together quickly the air within them will be compressed to form a cushion, and it can only escape gradually through the slot or opening 6.

The cushioning device is loosely mounted, preferably, by means of ball-and-socket joints between the two members *s* of a vehicle-spring or upon either the outer or inner 90 side of the same, as previously stated. These ball-and-socket-joint connections are clearly shown in Fig. 2 of the drawings and each comprise a ball member 13 and a socket member 14. The ball member may be clamped, 100 bolted, or otherwise secured, as at 16, or in the most convenient place between or adjacent to the members *s* of the spring, and it has at one of its ends a ball 15, which is adapted to move freely in a socket 17, formed 105 in the member 14. The latter, as shown, is formed of two parts adapted to be bolted or

otherwise secured together and to the closed end of one of the members 2 3. These ball-and-socket-joint connections are the same at both ends of the cushion and permit the body 5 of the vehicle, which is supported by the springs, to sway laterally without interfering with the sliding or telescoping movement of the two members 2 3. It will be noted that the lateral play of the axle and body 10 will not in any way interfere with the operation of the cushion, owing to the provision of these ball-and-socket connections.

From the foregoing description, taken in connection with the accompanying drawings, 15 the operation and advantages of the invention will be readily understood without requiring a more extended explanation.

Various changes in the form, proportion, and the minor details of construction may be 20 resorted to without departing from the principle or sacrificing any of the advantages of this invention.

Having thus described my invention, what I claim as new, and desire to secure by Letters Patent, is—

1. A pneumatic cushion for springs, com-

prising two tubular telescoping members, each closed at its outer end, the inner member having its inner end open and provided near its outer end with openings which coact 30 with the outer end of the outer member to regulate the admission and escape of air.

2. In combination with a spring having upper and lower members, a pneumatic cushion comprising two tubular telescoping members, each closed at its outer end, the inner member having its inner end open and provided near its outer end with openings which coact with the outer end of the outer member to regulate the admission and escape of air, 40 said cushion being disposed between the upper and lower members of the spring, and ball-and-socket-joint connections between the members of the spring and those of the cushion.

In testimony whereof I have hereunto set my hand in presence of two subscribing witnesses.

CALEB S. GURNEY.
